UNITED STATES PATENT OFFICE.

ZEMACH AUERBACH, OF NEW YORK, N. Y.

FILING RACK.

Application filed March 15, 1923. Serial No. 625,287.

To all whom it may concern:

Be it known that I, ZEMACH AUERBACH, a citizen of Russia, and resident of New York city, in the county of New York and State of New York, have invented certain new and useful Improvements in Filing Racks, of which the following is a specification.

My invention relates to improvements in the class of racks or holders for filing or index systems employing separate cards upon which memoranda and the like are kept for reference and other uses.

The object of my invention is to provide a rack or holder which will contain a maximum number of cards or similar material in a minimum space, such cards normally lying upon one another flatwise with a marginal portion of each card exposed to view, the rack being so arranged that it may be extended in length to permit ready access to any card and may be reduced in length when the cards are to be filed away for reference.

In carrying out my invention I provide a rack or frame having a plurality of members adapted to be moved with relation to one another, such as telescopically, in which a series of cards may be placed upon one another adapted to fill the rack from end to end when its members are closed or are in the short position, whereby when said members are extended with relation to one another the cards may be slid along the rack for access to any one of the cards, the arrangement being such that when the members of the rack are pushed together they will cause the cards to slide back to the normal position of assembly.

My invention also comprises novel details of improvement that will be more fully set forth hereinafter and then pointed out in the claims.

Reference is to be had to the accompanying drawings forming a part hereof, where-in-

Fig. 1 is a plan view illustrating my improved card index rack partially extended for use;

Fig. 2 is a section on the plane of line 2—2, in Fig. 1, showing cards in a different position and with a portion of the cards omitted;

Fig. 3 is a sectional detail on an enlarged scale substantially on line 3—3, in Fig. 1;

Fig. 4 is a detail of one of the clips for the cards;

Figs. 5 and 6 are detail views illustrating opposite sides of a card and attached clip;

Fig. 7 is a detail of a portion of a card;

Fig. 8 is a plan view illustrating the rack 60 closed;

Fig. 9 is an enlarged section on the plane of line 9—9, in Fig. 8;

Fig. 10 is an enlarged detail cross section on line 10—10, in Fig. 8, and 65

Fig. 11 is a detail perspective of one of the cards.

Similar numerals of reference indicate corresponding parts in the several views;

The rack comprises two main members, 1, 70 2 movably connected together adapted to contain a series of cards 3 flatwise upon one another with marginal portions exposed to view. The member 1 of the rack is shown comprising a flat base 1^a having spaced side 75 walls or ribs 1^b between which the cards are located and guided, and a wall 4 at one end of the base extending thereover between the walls 1^b adapted to cover adjacent ends of cards when the rack is closed. The wall 4 80 extends from the end wall 1^c. To retain the edge portions of the cards I have shown wires or bars 5 extending along and within the walls 1^b so that the sides of the cards will be beneath said wires. The wires may 85 be attached to the rack in any desired way. I have shown the wires joined substantially in U-like form at one end of the rack, having the integral cross bar 5^a at said end of the rack from which the wires pass through 90 holes 6, in end wall 1^c, and their opposite ends are each attached to one of the walls 1^b, as by solder, after being transversely bent and between the folded members of the side wall 1^b, as indicated in Figs. 8 and 9. 95 The folded upper edge of said walls may be slit at 7 for the purpose of receiving the ends of the wires.

The member 2 is shown in flat form having side walls 2^a spaced apart to slide along 100 the adjacent portions of walls 1^b. The base 2^b of member 2 is shown adapted to slide beneath the base 1^a of member 1 (Figs. 2 and 10), the outer end of member 2 having a transverse wall 2^c opposed to the transverse wall of 1^c of member 1. By preference member 2 has an interior wall 2^d that will lie upon base 1^a to cover the adjacent edge thereof, so that the latter will not interfere with the cards or the clips thereon 110 when the members 1, 2 are slid relatively to one another. The members 1, 2 may be made

of sheet metal bent and folded in the manner illustrated, whereby the base 1^a, side walls 1^b, end wall 1^c and outer wall 4 may be in a single piece of metal, and the base 5 2^b, walls 2^a, 2^c and 2^d are folded from a piece of metal, as shown in Fig. 2. The wall 2^c is shown formed by a folded portion of the metal. Side walls 2^a are provided with means to guide them along the walls 1^b of 10 member 1 telescopically, for which purpose I have shown the inner ends of the walls 2^a provided with laterally disposed projections 2^d to overlie the corresponding edges of the walls 1^b, whereby with the walls 2^a outside 15 of the adjacent parts of walls 1^b, the base 2^b beneath the base 1^a and the projections 2^d over the walls 1^b, the members 1 and 2 are slidably connected together. I provide 20 means to limit the outward movement of member 2 relatively to member 1. In the example illustrated the wires 5 at their end portions adjacent to member 2 are bent or extended outwardly at 5^b in the path of the projections 2^d so that the latter will abut 25 against the parts 5^d when member 2 is pulled out to its limit.

The arrangement described is such that a series of cards 3 may be placed within the rack, extending its full length when the 30 members 1, 2 are closed, the cards lying one upon another with margins of the cards exposed as at 3^a, which will be the condition when the cards are assembled for storage. When it is desired to use or inspect one of 35 the cards the members 1 and 2 will be pulled so that member 2 will be extended from member 1, to any desired extent, leaving a space between the wall 2^c and the nearest card of the series, and then the cards may 40 be shifted toward wall 2^c so that the desired card may be inspected, written upon or removed and replaced, (see Fig. 2). When the cards are to be replaced for storage it is merely necessary to push member 2 inwardly with respect to member 1 and thereupon wall 2^c will push all the cards together 45 to the normal or closed position, as illustrated in Fig. 8.

By the means described the length of 50 the rack may be relatively short when not in use and may be extended when the cards are to be used, thereby providing for a relatively large number of cards in a normally relatively short space, as distinguished from 55 racks heretofore proposed, as known to me, wherein a space is maintained between an end of the rack and the next adjacent card to enable the series of cards to be slid along the rack for access to the cards, which produces a rack longer than necessary for a 60 corresponding number of cards.

The cards may be of any desired or usual 65 form. In order to provide means to slide the cards manually along the rack without requiring the cards to be manipulated by

engagement therewith, as well as to protect the edges of the cards and to space and interengage them to slide them along the rack when the member 2 is pushed inwardly along member 1, I provide cards with interengaging 70 clips along their exposed marginal portion. I have illustrated clips 8 having hook-like end members 8^a adapted to engage the edges of the cards and having projections or prongs 8^b extending laterally 75 from the clips through the cards, whereby the clips are attached to the cards. In the example illustrated the projections 8^b extend outwardly through the cards for a short distance and then extend laterally 80 over the cards at 8^c, so that the projection of one card will nest with or engage the member 8^a of the next card, as illustrated in Figs. 2, 3, 8 and 9. The projection 8^b may be formed by slitting a base of the 85 clips to produce opening 8^d in the clip, and bending the projection outwardly and laterally. The clips may be attached to the cards by providing the latter with slits at 90 3^b cut in the cards to extend partly crosswise and partly lengthwise adjacent to the edges of the cards, as illustrated in Fig. 7, whereby the projections 8^b may be pushed through the cards at the slits 3^b and the adjacent edges of the cards may be tucked 95 under the members 8^a, the main bases of the clips being located on the under sides of the cards.

When member 2 is pulled out the operator may push the cards along the rack by 100 engaging the projections 8^b, and when member 2 is pushed inwardly its wall 2^c will engage the outer edge of the adjacent card and the corresponding projections 8^b will engage the adjacent parts 8^a of the successive 105 clips so as to slide the cards along the rack, one card pushing another as required.

My improved index rack may be used singly or several of them may be kept in a cabinet in a customary way for use. The 110 device is simple and relatively cheap to manufacture, effective in use, saves time and reduces wear on the cards.

Having now described my invention what I claim is:

1. A rack for cards comprising two members slidably connected together and provided with opposing end walls to receive a series of cards therebetween, and means to retain the cards flatwise in the rack.

2. A rack for cards comprising two members slidably connected together and provided with opposing end walls, means to limit endwise movement of said members relatively to one another, and means to retain cards flatwise in said members.

3. A rack for cards comprising two relatively movable members having spaced side walls and opening end walls adapted to receive cards flatwise therebetween, means to

- limit outward endwise movement of said members relatively to one another, and means to retain cards in said members. 40
4. A rack for cards comprising a member having a base, spaced side walls and an end wall, a second member having a base, side walls and an end wall, the base of one member being located along the base of the other member, means slidably connecting 45 said members together, means to limit outward endwise movement of said members relatively to one another, and means to retain cards flatwise in said members.
5. A rack for cards comprising a member having a base, spaced side walls and an end wall, a wall extending over and spaced from said base adjacent to its end wall, a second member having a base, side walls and an end wall, the base of one member being located 50 along the base of the other member, means slidably connecting said members together, means to limit outward endwise movement of said members relatively to one another, and means to retain cards flatwise in said members.
6. A rack for cards comprising a member having a base, side walls and an end wall, wires extending along said side walls and spaced from the base to receive cards between 55 the wires and the base, said member being provided with stops, a second member comprising a base, side walls and an end wall and having means slidably connecting it with the first-named member and to limit 60 the outward movement of the second member along the first member, the end walls of said members opposing each other to receive cards therebetween, whereby the end wall of the 65
- second-named member will push cards along the first-named member.
7. A card rack comprising a base provided with spaced side walls and an end wall, wires extending along said side walls and spaced from the base, said wires having end portions secured to the side walls and being 70 formed into stops adjacent thereto projecting outwardly, and a second member having side walls and an end wall opposed to the first-named end wall, the side walls of the second member being provided with means 75 cooperative with the side walls of the first member to retain said members in slidable engagement and adapted to engage said stops.
8. A card rack comprising a member having a base and walls to retain cards, a second member having a base, an end wall and a wall spaced from the base, the base of the first-named member being received in the space between the base and second-named 80 wall of the second named member, and means to retain said members in slidable engagement.
9. A card having a clip provided with a hook-like member at one edge, and a lateral 85 projection extending through the card, the outer end of said projection being turned to extend over the card.
10. A card having a slit in combination with a clip having a hook-like member engaging an edge of the card and provided with a projection extending through said slit, the outer end of said projection being turned to extend along the card. 90

ZEMACH AUERBACH.
